UNITED STATES PATENT OFFICE.

HOMER A. WOODS, OF INDIANAPOLIS, INDIANA.

EGG-CANDLING ATTACHMENT FOR PORTABLE LANTERNS.

1,311,106.

Specification of Letters Patent. Patented July 22, 1919.

Application filed January 25, 1918. Serial No. 213,657.

To all whom it may concern:

Be it known that I, HOMER A. Woods, a citizen of the United States, residing at Indianapolis, in the county of Marion and State of Indiana, have invented a new and useful Egg-Candling Attachment for Portable Lanterns, of which the following is a specification.

It is the object of my invention to provide a simple and inexpensive egg-candling device for attachment to portable lanterns, which can be easily adjusted to proper position, which is connected in circuit only while the egg is being tested, the connection being made by the egg itself as it is put in testing position, and which will be properly connected when attached to the lantern even by a novice.

The accompanying drawings illustrate my invention. Figure 1 is a plan view of a lantern with my egg-candling attachment thereon, with the lantern cover removed to show the interior connections; Fig. 2 is a side elevation of such lantern and egg-candling attachment; Fig. 3 is a diagrammatic view showing the electrical connections; Fig. 4 is a partial front view of the egg-candling attachment, with the sight tube broken away; Fig. 5 is a partial rear view of such egg-candling attachment, with the sight tube broken away; Fig. 6 is an enlarged section on the line 6—6 of Fig. 4; Fig. 7 is a section on the line 7—7 of Fig. 4; and Fig. 8 is a section on the line 8—8 of Fig. 5.

The portable lamp comprises a casing 10 with a rear carrying handle 11 and a carrying bail 12, and is provided with a removable top 13. On the front of the casing 10 is mounted a reflector in a reflector housing 14 the end of which is screw-threaded, and within the reflector is an incandescent bulb 15 which is energized by two dry cells 16 and 17 within the casing 10. The lamp 15 is connected between the zinc binding post 18 of the cell 17 and the carbon binding post 19 of the cell 16. There is also a control switch 20 which is mounted on the rear of the lantern so that its operating handle can be operated by the thumb of the hand grasping the handle 11. The normal connections of this switch are between the zinc binding post 21 of the cell 16 and the carbon binding post 22 of the cell 17 so that the closing of 55 the switch 20 completes the circuit for the

My egg-candling attachment is mounted on the forward end of the reflector housing 14, and comprises a screw-threaded cup-shaped member 25 (Fig. 6) which may be 60 screwed on to the screw threads on the reflector housing 14. This cup-shaped member is centrally perforated and furnishes a pivotal support for a hood 26, which is correspondingly perforated and at the perforation is provided with a turned edge 27 which folds around the edge of the perforation of the cup-shaped member 25 so as to furnish the pivotal support. By this means the hood 26 may be adjusted to upright position 70 regardless of the position the cup-shaped member 25 may take on account of the matching of the screw threads thereon and on the reflector housing 14; and in order to hold the hood 26 in any desired adjusted 75 position on the cup-shaped member 25 such hood is provided with a spring latch 28 the finger 29 of which may project through any desired one of a circular series of holes 30 arranged around the pivotal connecting axis 80 of the hood 26 and cup-shaped member 25, as clear from Fig. 5. The hood 26 is open at the forward end, and is preferably cut away on a slant, as shown in Fig. 2, to allow the convenient placing of eggs therein 85 by the operator who stands in front of the hood and looks down through a slanting sight tube 31 entering the hood 26 from the top. In order that the egg when placed in position for testing may cause the lighting 90 of the lamp 15, a spring switch 35 is mounted within the hood 26 and is provided with an annular operating end 37 which registers with the perforations in the hood 26 and the cup-shaped member 25 when it 95 is pressed to the dotted line position (Fig. 6) by the placing of an egg in position, these three registering perforations being of sufficient size so that the end of an ordinary egg can be pushed partly therethrough, while 100 the whole egg cannot pass through, as indicated by the drawing. The switch 35 consists of a spring strip of metal which is provided with clamping tabs 38 by which it is clamped to a strip of insulation 39 clamped 105 against the vertical part of the hood 26 by clamps 40, such vertical part of the hood being cut away so that the clamping tabs 38 are out of contact therewith. Also mounted on this insulating strip 39 and out of contact with the metal part of the hood 26 is a 110 contact 41 which is engaged by the spring

switch 35 when it is pushed to the dotted line position (Fig. 6) but is out of engagement therewith when such switch is in the normal or full line position, to which position it tends to move by its inherent resiliency. If desired, the spring switch 35 may be guided and limited in its movements by a member 42. One of the tabs 38 and the contact 41 are provided with connecting wires 44 and 43, which are suitably attached in any convenient way, and these wires lead through a hole 45 in the cap 13 to the interior of the casing 10, where a fan-shaped piece of insulation 46 is provided to fit upon the carbon binding post 22 of the cell 17, from which binding post the wire from the switch 20 is removed. The wire 44 is clamped on this binding post 22 by the clamping screw of such binding post, which 20 clamping screw also holds the fan-shaped piece of insulation in place. This fan-shaped piece of insulation is provided with a binding post 47, which is separated from the binding post 22, and to this binding post 47 are attached by a suitable clamping screw both the wire 43 and the wire from the switch 20, the latter of which wires was the one which was normally attached to the binding post 22. The switch 20 and the 30 spring switch 35 are now in series.

When it is desired to test an egg, the operator looks down into the hood 26 through the sight tube 31, and places the end of the egg 50 to be tested into the hole in the annular switch operating end 37 of the spring switch 35, pushing it from the full to the dotted line position (Fig. 6) and thereby moving such switch into engagement with the contact 41. The switch 20 having 40 already been closed, this movement of the switch 35 closes the circuit with a lamp 15, which is thereby illuminated; and the light from the lamp 15 shines into and through the egg, so that the observer looking down 45 through the tube 15 and shielded from the direct rays of the light may inspect the interior of such egg and determine its quality.

Eggs can be tested in this manner very rapidly, and without any visual or nasal 50 discomfort. If desired, in order to prevent accidental breakage of eggs, a cushion 51 may be provided for the annular member 37 of the switch 35 to bear against when the switch is moved to circuit-closing position, 55 such cushion also being perforated in registry with the perforations in the hood 26. If desired, the perforation in the cushion 51 may be slightly smaller than the other perforations, so that it may act as a cushion 60 directly against the egg itself.

I claim as my invention:

1. An egg-candling attachment for portable electric lanterns, comprising a screw-threaded member for attachment to a screw-threaded light-containing part of the lan-

tern, a hood pivotally mounted on said screw-threaded member so that it can be adjusted to the desired position regardless of the position taken by the screw-threaded member, and a spring latch for holding said 70 screw-threaded member and hood in any desired adjusted position, said spring latch being mounted on one of said two pivotally connected parts and cooperating with a circular series of holes in the other of said parts, 75 said hood and said screw-threaded member being provided with an opening to allow the light to enter the hood.

2. An egg-candling attachment for portable electric lanterns, comprising a screw-threaded member for attachment to a screw-threaded light-containing part of the lantern, and a hood pivotally mounted on said screw-threaded member so that it can be adjusted to the desired position regardless of 80 the position taken by the screw-threaded member, said hood and said screw-threaded member being provided with an opening to allow the light to enter the hood.

3. An egg-candling attachment for portable electric lanterns, comprising a screw-threaded member for attachment to a screw-threaded light-containing part of the lantern, a hood pivotally mounted on said screw-threaded member so that it can be 95 adjusted to the desired position regardless of the position taken by the screw-threaded member, and a spring latch for holding said screw-threaded member and hood in any desired adjusted position, said hood and said 100 screw-threaded member being provided with an opening to allow the light to enter the hood.

4. An egg-candling attachment for portable electric lanterns, comprising a screw-threaded member for attachment to a screw-threaded light-containing part of the lantern, a hood pivotally mounted on said screw-threaded member so that it can be adjusted to the desired position regardless 105 of the position taken by the screw-threaded member, said hood and said screw-threaded member being provided with an opening to allow the light to enter the hood, and a sight tube carried by said hood and opening thereinto.

5. An egg-candling attachment for portable electric lanterns, comprising a screw-threaded member for attachment to a screw-threaded light-containing part of the lantern, a hood pivotally mounted on said screw-threaded member so that it can be adjusted to the desired position regardless of the position taken by the screw-threaded member, a spring latch for holding said 125 screw-threaded member and hood in any desired adjusted position, said hood and said screw-threaded member being provided with an opening to allow the light to enter the hood, and a sight tube carried by said hood 130

and opening thereinto from one side thereof, whereby the pivotal adjustment of the hood on said screw-threaded member permits said sight tube to be brought to any desired 5 position.

6. An egg-candling attachment for portable electric lanterns, comprising a screw-threaded member for attachment to a screw-threaded light-containing part of the lantern, a hood pivotally mounted on said screw-threaded member so that it can be adjusted to the desired position regardless 10 of the position taken by the screw-threaded

member, said hood and said screw-threaded member being provided with an opening to 15 allow the light to enter the hood, and a control switch mounted within said hood so as to be operated by an egg which is placed in testing position within the hood.

In witness whereof, I have hereunto set 20 my hand at Indianapolis, Indiana, this 17th day of January, A. D. one thousand nine hundred and eighteen.

HOMER A. WOODS.
